AUTOMATIC ANTIFREEZE SYSTEM

Filed Jan. 28, 1929

INVENTOR
CHARLES A. BAUGHMAN.

BY -

A. D. Jackson
ATTORNEY.

UNITED STATES PATENT OFFICE

CHARLES A. BAUGHMAN, OF FORT WORTH, TEXAS

AUTOMATIC ANTIFREEZE SYSTEM

Application filed January 28, 1929. Serial No. 335,681.

My invention relates to freeze preventing means and more particularly to means for preventing the freezing of radiators of motor vehicles; and the object is to provide simple devices in a radiator which will be actuated automatically to prevent freezing of the radiators and to provide devices for automatically starting and stopping the anti-freezing means. Other objects and advantages will be fully explained in the following description and the invention will be more particularly pointed out in the claims.

Similar characters of reference are used to indicate the same parts throughout the several views.

Fig. 1 is a diagrammatic view, showing a radiator and a battery and a transformer, the radiator being partly in section.

Fig. 2 is a detail sectional view of the automatic heating means.

Similar characters of reference are used to indicate the same parts throughout the several views.

The drawings show a radiator 1 of ordinary type and a battery 2 of approved type. A metal plate 3 is attached to the bottom of the radiator 1. A thermostat, consisting of a metallic tube 4 and a metallic rod 5 projecting through the tube 4, is mounted in 25 and projects through the plate 3 and into the radiator 1. The rod 5 and the tube 4 must have different coefficients of expansion from each other. Current wires 6 and 7 are provided and wire 6 is connected to the battery 2 and run through the plate 3 and insulated therefrom and connected to the heating wires 8. Both wires 6 and 7 are electrically connected to the transformer 9. A short wire 10 is run through the plate 3 30 and insulated therefrom and electrically connected to the heating wires 8. The heating wires 8 are mounted in a cavity in the plate 3. The object of the wires 8 is to heat a portion of the bottom of the radiator. This heat will be transmitted to the water in the radiator. This heating of the water adjacent to the wires 8 will set up a circulation of the water in the radiator, and such circulation of the water warmed by 35 the wires 8, will prevent freezing of the

water in the radiator. The wire 10 is connected to a metallic block 11 which is insulated from the plate 3. The block 11 has a contact point 13. The wire 7 is electrically connected to the plate 3 and the plate 3 and tube 4 and rod 5 are in electrical connection, being metal in contact with metal. The rod 5 is so positioned that when the water becomes cold, the thermostat will contract and bring the rod 5 in contact with the contact point 13 so that a circuit will be closed for heating the wires 8. When the water in the radiator 1 becomes warm, the tube 4 will expand and so draw the rod 5 out of contact with the point 13 and break the circuit. If 60 the water is again cooled towards the freezing point, the thermostat will again contract and bring the rod 5 in contact with the point 13. These operations will be automatic.

The transformer 9 is provided so that when 70 a car is parked, a connection can be made with a supply source of electricity for heating the water in the radiator without using the battery 2. It is apparent that the driver can stop his car and connect the transformer 75 with any supply source and warm the water in the radiator. This can be done at the ordinary filling or service stations.

What I claim is—

1. In a motor vehicle provided with a battery and a radiator; means for utilizing said battery to heat the water in the radiator comprising a metallic plate attached to the lowest point of the radiator and provided with a cavity therein, heating wires mounted in 80 said cavity and insulated from said plate, one current wire electrically connected to said heating wires and to said battery, another current wire electrically connected to said heating wires to cause an electric circuit through said heating wires, a metallic contact block attached to said plate and insulated therefrom, a thermostat mounted in 85 said plate and projected into said radiator and provided with a rod adapted to contact with said block, means electrically connecting said heating wires and said block, and means electrically connecting said thermostat with said battery.

2. In a motor vehicle provided with a ra- 100

diator; a metallic heating means attached to said radiator at its lowest point, means for electrically connecting said heating means to a supply source of electricity for heating the heating means, a thermostat attached to said radiator and projected thereinto and provided with a movable contact making point, a metallic block attached to said radiator and insulated therefrom and provided with a contact point adapted to complete a circuit with said movable contact point, means for electrically connecting said block to said heating means, and means for electrically connecting said thermostat with said supply source of electricity.

In testimony whereof, I set my hand, this 23rd day of January, 1929.

CHARLES A. BAUGHMAN.
